UNITED STATES PATENT OFFICE

LEROY P. STERLING, OF WILLIAMSPORT, PENNSYLVANIA, ASSIGNOR TO A C SPARK PLUG COMPANY, OF FLINT, MICHIGAN, A COMPANY OF MICHIGAN

DETACHABLE FILTER COVER

Application filed August 10, 1928. Serial No. 298,843.

This invention relates to containers, and has particular reference to a container for receiving the filtering unit of oil filters used on automotive vehicles.

5 Oil filters as at present used on automotive vehicles comprise an outer container which houses an inner filtering unit. The outer container usually has the bottom and cover crimped to the sides so that it is necessary to 10 destroy the container if it is desired to remove the inner filtering unit, thereby prohibiting replacement of the latter and necessitating the throwing away of the entire filter.

It is an object of the present invention to 15 construct containers which will have a removable end piece so that the inner filtering unit may be removed and a new one supplied without destroying the container. This will enable the same container to be used indefinitely, resulting in a decreased cost in the 20 price of the filter.

I accomplish the object of the invention in the preferred form by forming a flange at one end of the container, and providing a 25 combined ring and supporting bracket which surrounds the container and abuts underneath against the flange. A gasket is seated on the flange and a cover over the gasket and over this cover, there is provided a suitably 30 shaped ring which conforms to the shape of the cover edge and of the ring abutting the flange of the container. One of the rings has bolt openings while the second ring is preferably provided with slots for the reception 35 of the shanks of bolts which are secured by means of wing nuts. By tightening the wing nuts, the cover may be secured to the container in liquid tight relation.

The combined ring and bracket also serves 40 as a means for supporting the container, the bracket portion consisting of an integral bent flange extending at right angles to the plane of the ring and having a number of openings by means of which it may be attached 45 to the dashboard or other suitable part of the vehicle.

As a modification of the preferred form, I 50 may use instead of the combined ring and bracket, a plain ring having a suitable number of loops in each of which there is fas-

tened an eye bolt, the shank of which is adapted to enter slots in the ring member over the cover. The parts are retained in a liquid tight relation by means of wing nuts screwed onto the bolts.

The invention is disclosed on the accompanying drawings in which:

Figure 1 is a plan view of the preferred form of container with parts broken away.

Figure 2 is a side view of the structure of Figure 1 with parts broken away and shown in section for purposes of clearer illustration.

Figure 3 is a view similar to Figure 1 of a modification.

Figure 4 is a view similar to Figure 2 of the modification shown in Figure 3.

Referring to the numbered parts on the drawing, 10 indicates the filter as a whole comprising the container 11 having the inner filtering unit 12 secured at one end by means of a suitable fitting 14, which also serves as the inlet to the filter. The outlet to the filter is shown at 16 to which a suitable pipe may be connected for leading the filtered oil to any desired point.

The container 11 has at its upper edge a flange 18 which in turn is upwardly bent as at 20, so that the flanges 18 and 20 form a seat for the reception of a gasket 22. Seated on the gasket 22 is a cover 24 preferably hollowed as shown at 25 and having an outwardly turned flange 26, which is seated within and conforms to the seat formed by the flanges 18 and 20 of the container.

Surrounding the container and abutting the lower portion of the flange 18 is a combined ring and bracket 28, the ring portion 29 of which comprises the annular vertical flange 30 and the horizontal annular flange 32. The ring portion 29 has a lateral extension as shown at 34, which has a downwardly bent portion 36 forming a bracket or arm by means of which the container is secured to any suitable portion of the machine with which the filter is used. This bracket or arm 36 has suitable openings as shown at 38 for the reception of bolts or pins for securing the arm to its support.

Seated on the flange 26 of the cover 24 is a

ring member 40 having the vertical flange 42, which rests on the flange 26, and the horizontal flange 44, which has a plurality of pairs of forks 46 forming slots 47 for the reception of the shanks 48 of bolts 50, the lower portion of which is squared as shown at 52 to conform to the square opening 54 in the ring 28. The bolts 50 have wing nuts 56 which seat against the prongs 46 defining the slots 47 in the upper ring member 40.

10 When the wing nuts 56 are tightened the flange 42 of the ring 40 will press the flange 26 of the cover 24 down onto the gasket 22 resting on the flange 18 of the container 10 and form a liquid tight connection.

15 If desired, the shanks 48 of the bolts 50 may have secured thereto in any suitable way the ring member 58, the purpose of which is to hold the bolts 50 rigid with the ring 28, although these additional rings 58 may be omitted if desired.

Referring to the species of Figures 3 and 4, it will be seen that in place of the combined ring and bracket member 28 of Figures 1 and 2, I make use of a ring 60 having a plurality of loops 62 around its periphery and in which loops there is secured by means of a bolt or rivet 64, the eye 66 of an eye bolt 50'. The shank 48 of this bolt enters suitable slots 47' defined by the prongs 46', on the upper ring member 40' which is essentially the same as the corresponding ring member 40 in Figure 2, the difference residing in the provision of an additional flange 70 which rests on the edge 72 of the cover 24', which in this instance is a flat sheet.

20 Instead of forming the flange 18 of Figure 2 directly on the container, I employ the separate annular member 76, which has the flange 18 integral therewith, and which member is permanently secured to the upper portion of the container.

In order to replace the filtering unit 12 of either species, the wing nuts 56 are unscrewed, which will release the ring members 40 or 40' and permit the removal of the covers 24 or 24', which in turn will allow access to the filtering unit 12 so that it may be removed and a new unit inserted. After 25 the new unit is inserted, the covers 24 or 24' are set in place, the rings 40 or 40' applied and the wing nuts 56 screwed onto the bolts which will clamp the connections in liquid tight relation to the container 10.

30 The flange 18 of Figure 2, or the corresponding structure of Figure 4, need not necessarily be applied at the top of the container. The connection may be placed at the center in which case the cover will be cup-shaped and fit well down over the upper portion of the filtering unit.

I claim:

1. In a container, a cover, a unitary supporting ring and bracket for said container, and means connected with said ring-bracket

for permanently and rigidly securing said cover to said container.

2. In a container, a flange thereon, an integral supporting ring and bracket associated therewith the ring portion thereof abutting said flange, a flange on said supporting ring, a cover resting on said container flange, a securing ring resting on said cover, a flange on said securing ring, and means extending between said ring flanges to hold said cover on said container. 70 75

3. The combination of claim 2, said means comprising bolts and nuts, one of said flanges having polygonal openings for the reception of a correspondingly shaped part of said bolts and the other flanges having slots for the reception of the ends of said bolts. 80

4. In a container, a cover, a unitary supporting ring and bracket for said container, and means connected with said ring-bracket for securing said cover to said container, said means comprising a holding member on said cover and connections between said ring-bracket and member. 85

5. In a container, a cover, a unitary supporting ring and bracket for said container, and means connected with said ring-bracket for securing said cover to said container, said means comprising a ring associated with said cover and bolts extending between said ring-bracket and said cover ring. 90 95

6. In a container, a flange thereon, a ring for supporting said container at said flange, a cover and means associated with said cover and connected to said ring for holding said cover on said container, said ring also constituting a supporting bracket. 100

7. In a container, a flange thereon, a ring abutting said flange, a cover resting on said flange, a ring resting on said cover, and means extending between said rings for holding said cover on said container, said rings having right angularly turned flanges for the reception of said means, one flange having polygonal openings and the other flange slots in which said means is received. 105 110

8. In a container, a right angularly turned annular flange on said container, a ring surrounding said container and abutting said flange, a mounting or supporting bracket formed integral with said ring, a flange on said ring extending away from the container, a cover, a flange on said cover resting on said annular flange, a ring adapted to be positioned over said cover flange, a flange on said last named ring, and means for securing said rings together through their flanges. 115 120

In testimony whereof I affix my signature.
LEROY P. STERLING.
